United States Patent Office

Des. 218,203

Patented July 28, 1970

218,203

STEP FOR BOATS

Bernard M. Vevea, 3130 7th Ave. N.,
Anoka, Minn. 55810

Filed July 18, 1969, Ser. No. 18,263

Term of patent 14 years

Int. Cl. D12—14

U.S. Cl. D71—1

FIG. 1

FIG. 2

FIG. 3

FIG. 4

FIG. 5

FIG. 1 is a perspective view of the step for boats, showing my new design;

FIG. 2 is a top plan view thereof;

FIG. 3 is a front elevational view thereof;

FIG. 4 is a side elevational view thereof; and,

FIG. 5 is a bottom plan view thereof.

I claim:

The ornamental design for a step for boats, as shown.
